ROTARY LIPSTICK HOLDER

Alexander S. Mackey, Ottawa, Ontario, Canada,
assignor to Scovill Manufacturing Company,
Waterbury, Conn., a corporation of Connecticut

Application March 12, 1946, Serial No. 653,860

7 Claims. (Cl. 206—56)

1

This invention relates to holders for such articles as lipsticks. More particularly, the invention deals with devices of this kind constructed of a minimum number of parts wherein the holder proper or cartridge is arranged in its entirety within a casing and includes a threaded or helix portion, by means of which indentures or projections formed from the material of the casing will operate in the helix in providing rotary and longitudinal movement of the cartridge of the device with respect to the casing in projecting the lipstick and in drawing the lipstick into the casing. Still more particularly, the invention deals with devices of this kind wherein the casing includes a relatively wide opening in its side wall sufficient to expose a roughened surface of the helix thereto to be accessible by a digit of a hand while grasping the device at one end portion thereof. The novel features of the invention will be best understood from the following description when taken together with the accompanying drawing, in which certain embodiments of the invention are disclosed and in which the separate parts are designated by suitable reference characters in each of the views, and in which:

Fig. 1 is an exploded view showing a side elevation of one form of holder which I employ with the cover detached with respect thereto and showing the lipstick extended.

Fig. 2 is an enlarged sectional view of the holder with the cap removed and showing the cartridge in elevation with the lipstick retracted.

Fig. 3 is an enlarged sectional view at right angles to the showing in Fig. 1 and omitting part of the lipstick material.

Fig. 4 is a section on the line 4—4 of Fig. 3.

Fig. 5 is a view similar to Fig. 3 showing a modification and showing the cartridge in a lowered position in elevation.

Fig. 6 is a section on the broken line 6—6 of Fig. 5.

Fig. 7 is a view similar to the holder of Fig. 1, showing the cartridge in a different position and showing a modification.

Fig. 8 is a sectional view at right angles to the structure shown in Fig. 7 with the cartridge in partially extended position.

Fig. 9 is a view similar to Fig. 5 showing a part of the construction and illustrating another modification.

Fig. 10 is a side elevation of the structure as seen in Fig. 9; and

Fig. 11 is a side view of a part of a lipstick case showing another modification.

2

The structure shown and described in this application constitutes a continuation-in-part of the structure shown and described in my prior application Ser. No. 569,664, filed December 22, 1944. 5 The present application includes a slight modification of the structure shown, more particularly in Fig. 11.

In Figs. 1 to 4 inclusive, I have shown at 12, the outer casing or jacket of a holder which includes an enlarged head or closure 13 at one end, providing on the periphery of the casing a shoulder 14 against which the lower end of a thimble shaped cap or cover 15 is adapted to rest. The cover 15 is shown in extended position in Fig. 1, preparatory for attachment to the holder when the lipstick 16 is withdrawn into the casing or shell 12.

The lipstick 16 is arranged in a holder or cartridge 17 comprising an elongated body divided by a central partition wall 18 into recesses 19 and 20 forming tubular end portions of said cartridge. The partition 18 includes a raised conical member 21 extending into the recess 19 and apertured centrally, as seen at 22, so that in pressure feeding the lipstick 15 into the recess 19, the lower end of the lipstick will be spread over the conical member and forced into firm engagement with the walls of the recess 19 to securely retain the lipstick against displacement therefrom. The aperture 22 provides a vent for the discharge of air as the snugly fitting lipstick is forced downwardly in the recess 19.

On the periphery of the cartridge 17 is formed a spiral, thread or helix 23, the outer surface of which is knurled or otherwise roughened. This thread or helix terminates at one end to form a circumferential shoulder 24 which is adapted to abut in an inturned rim or flange portion 25 bordering the opening 26 at the discharge end of the casing 12. The opening 26 is sufficiently larger than the diameter of the lipstick 16, so as to provide a free passage of the lipstick therethrough without danger of scraping the surfaces thereof. In assemblage, the cartridge with the lipstick 45 therein is inserted into the casing before the flange 25 is turned inwardly. After the assemblage has been made, this flange is then turned inwardly to retain the cartridge 17 against displacement. The outside diameter of the thread 50 or helix portion of the cartridge is made to fit snugly but yet freely in the bore of the casing 12 to be free to rotate therein and move longitudinally thereof.

The casing 12 has a substantially elliptical aperture 27 formed in one wall thereof substan-

tially centrally with respect to the ends of the casing, and is sufficiently wide to expose the helix 23 therethrough to be engaged by a digit of a hand, as will clearly appear from a consideration of Fig. 3 of the drawing, and as will also be apparent from a consideration of Figs. 1 and 4. At the sides of the opening 27 are arranged thread or helix engaging members 28 which are in the form of lugs, and these lugs are normally within the contour of the cylindrical walls of the casing 12. Prior to assemblage the lugs 28 are turned inwardly, as clearly seen in Fig. 4. In placing the cartridge 17 in the casing, the lugs 28 engage in the recesses between the thread or helix 23, and it will thus be seen that upon rotation of the cartridge, the latter will be elevated or retracted relatively to the casing. The lugs 28 are turned inwardly, as clearly seen in Fig. 4 to engage in the recesses between the thread or helix 23. In this connection, it will be apparent that the aperture 27 is disposed in an angular relationship so that the members or lugs 28 will be so spaced one with respect to the other as to correspond to the pitch of the thread or helix 23. When the cartridge is fully retracted, as seen in Fig. 2 of the drawing, the lipstick will be substantially retained within the upper end of the casing 12. A new lipstick may protrude slightly therefrom, as seen in Fig. 2, in which event, the cover 15 is made sufficiently longer and with a domed top 29 to clear the protruding rounded end 30.

In Figs. 5 and 6 of the drawing is shown another adaptation of the invention wherein a casing 31 is employed which differs from the casing 12 in several respects. First this casing has an open slightly enlarged end 32 having spaced circumferential beads 32a. A cap 33 is adapted to be inserted into the end 32 and the sleeve portion of this cap includes opposed nibs 34 which are adapted to be snapped into the lowermost bead 32a of the enlarged end 32. This type of construction is adaptable to devices of the kind shown in Figs. 1 to 4 inclusive, and at the same time, the closed end as at 13, is also adaptable to the structure of Figs. 5 and 6 as well as the other figures.

The casing 31 further differs from the casing 12 in providing an opening 35 which can be narrower than the opening 27 and is preferably longer than the opening 27, and instead of having the lugs 28 therein, a cartridge 36 or the helix 37 thereof has a threaded engagement with three series of vertically spaced nubs or elongated indentations 38. The series in the construction shown comprising three nubs arranged in longitudinal alinement on the casing 31 and three series of these are spaced circumferentially to register with the pitch of the helix 37 in the cartridge. This construction provides substantially the equivalent of a continuous thread in the casing 31, but at the same time, minimizes the frictional engagement by reducing the surface contact between the casing and the helix of the cartridge. Aside from the arrangement of the helix on the cartridge 36, this cartridge otherwise will be of the same general structure internally as the cartridge 17. In this connection, the same will be true of the cartridges shown in Figs. 7 to 10 inclusive.

The casing 31 includes an inturned flange or rim 39, similar to the rim 25. However, by employing a detachable cap 33, the rim 39 may be preformed and the cartridge inserted into the casing 31 through the lower open end thereof.

This type of construction permits renewal of the cartridge. However, it must be apparent that with the several devices shown, new lipstick inserts may be inserted into any of the cartridges, in that it will be relatively simple to clean out the recess in the cartridge for the reception of the new lipstick. At this time, it is also well to bear in mind that the cartridge may be constructed of plastic material and thus economically produced as a casting. This may be fitted in a metallic casing, but on the other hand, in some instances, the casing itself and cap 15 may all be composed of plastic materials. The turned in flange 25 may be formed by heating the end 15 of the casing to facilitate the inward flanging thereof.

In Figs. 7 and 8 of the drawing is shown a slight modification of the structure shown in Figs. 1 to 4, and 5 and 6, combining certain general features of both forms of constructions shown in these figures. In other words, in Fig. 8, the casing 40 of the general contour of the casing 31 is employed including the lower enlarged beaded portion 41 and detachable cap 42 and an upper inturned flange 43 at the discharge open end of the casing. The wall of the casing 40 instead of having an elongated aperture, like the aperture 35, is provided with an angularly arranged and substantially elliptical aperture 44, bordered at upper and lower edges in inturned lips 45 and 46, which are adapted to enter the recess above and below the spiral, thread or helix 47 of a holder or cartridge 48. These lips will serve to engage the helix in the manner clearly illustrated in Fig. 8 to feed the helix longitudinally of the casing 40 as the helix is rotated by the digit of a hand engaging the knurled or roughened surfaces provided on the helix as in the other forms of construction shown. In the several forms of construction which I employ, the apertures or openings are all arranged substantially centrally of the casing of the holder, so as to provide a grip of the casing below the opening with the casing arranged in the hand, in such manner that the thumb of the hand can be moved across the opening engaging knurled portion of the helix in rotating the cartridge to positively feed the same upwardly and downwardly in the casing, thereby providing a one hand operation and use of the lipstick, in contrast to most devices of this kind which require the use of two hands in the adjustment or feed of the lipstick in the holder.

In Figs. 9 and 10 of the drawing is shown a slight modification of the structure illustrated in Figs. 5 and 6, the sole difference being in substituting for the three circumferentially spaced series of three longitudinally aligned nubs, three elongated nubs or indentations 49 arranged longitudinally at an angle common to the pitch of the helix 50 on the cartridge 51, these elongated nubs or indentations being in the form of a portion of a thread of the character of a buttress thread. It will appear from a consideration of Fig. 9 of the drawing that the upper walls 52 of the members 49 are relatively sharp to produce sharp angular engagements with the lower edges of the coils of the helix. This construction will provide a positive feed of the cartridge longitudinally of the casing 53 in both directions. This is also true of the construction shown in the other figures, thus longitudinal play of the cartridge is minimized in all forms of construction shown.

In Fig. 11, I have shown a slight modification which incorporates the spacing features of some

of the nubs, as illustrated in Figs. 5 and 6, while using elongated nubbins or lugs of the type disclosed in Figs. 9 and 10. In Fig. 11, 54 represents the outer casing of the device, which may be generally similar to the casings 12, 31, 40 and 53. The casing 54 has a large rectangular opening 55 at the lower portion thereof, and the walls of the casing have three longitudinally and circumferentially spaced and slightly elongated inwardly pressed lugs or nubs, as at 56, 57 and 58, these nubs being arranged at an inclined plane and in a spiral relationship one with respect to the other to match a spiral groove 59 in a holder or cartridge 60, similar to the cartridge 51 or the cartridge 36 and 48, the only difference being that the spiral groove 59 is narrower and disposed in an opposite direction so as to require rotation in a right to left direction by the thumb of a hand in feeding a lipstick outwardly rather than in the left to right direction, as disclosed in the other figures. The cartridge 60 has between the spiral groove 59 the roughened or grip surfaces 61, which facilitates rotation of the cartridge, and similar to the roughened or grip surfaces shown in Figs. 5, 8 and 9.

Considering Fig. 11 of the drawing, it will appear that the uppermost nub 56 is disposed above the aperture 55, the nub 57 is disposed at one side of the aperture 55, whereas the nub 58 is disposed below the aperture 55 and the three nubs are spaced circumferentially and positioned in the spiral path defined by the spiral groove 59 so as to maintain engagement with the groove in the screw feed action of the cartridge. The spacing of the nubs is such as to facilitate the use of a relatively short cartridge and yet at all times maintain threaded engagement with at least one of the nubs 56, 57 and 58.

By providing what may be termed the left hand thread on the cartridge 60, as disclosed in Fig. 11, rotation of the cartridge in outward feed of the lipstick can be more readily accomplished in a one hand operation of the device.

The structure of Fig. 11 is only shown in part to illustrate the modification employed, but the casing of Fig. 11 as well as the holder, aside from the modified structures disclosed, will be the same as that shown in the other figures. Here particular reference is had to the means checking movement of the cartridge or helix in its movement in both directions in the casing, as well as the means for supporting the lipstick in the cartridge, as more specifically disclosed in Fig. 3 of the drawing.

By virtue of the arrangement of the various lugs, nubs or other projecting thread or helix engaging members, the same may be preformed on the casing in that the cartridge is adapted for threaded engagement therewith for insertion into the casing regardless of which end of the casing is employed for insertion of the cartridge.

From the foregoing, it will be apparent that a minimum number of parts are employed in the construction of the holder, and furthermore the parts can be simply and economically formed of metal, plastic materials, or a combination of such materials. Furthermore, it will be apparent that the over-all size of the resulting holder is minimized, and in this respect, it must be kept in mind that sizes of parts in the accompanying drawing are exaggerated slightly for clearance in illustration, and do not necessarily represent the actual sizes employed in the finished product. It will also be apparent that with the forms of construction shown in Figs. 5 to 10 inclusive, em-

ploying the enlarged head or the equivalent thereof, a stop shoulder is formed similar to the shoulder 14 to limit movement of the cap, a cap being employed on all holders, and when applied, the resulting unit will represent a cylinder having a common diameter through the length thereof.

By providing a lipstick supporting cartridge which in its entirety is disposed within the bore of the casing, it will be apparent that when the usual cap, such as the cap 15 of Fig. 1 is supported on the casing, any relative rotary movement between the casing and cap will not transmit movement to the cartridge. This has been an objection to many devices of this kind where the cap has operatively engaged the cartridge or its equivalent and relative rotary movement as mentioned above would contribute longitudinal movement to the cartridge, which would operate to jam the lipstick material in the closed end of the cover. With the present constructions disclosed, it is essential to remove the cap to expose the opening in the casing in order to operate the cartridge in either direction in the casing.

Having fully described my invention, what I claim as new and desire to secure by Letters Patent is:

1. A lipstick holder comprising an outer tubular body having a longitudinal bore, a discharge opening at one end of said bore, a lipstick cartridge having a threaded portion on the periphery thereof extending substantially throughout the full length of the cartridge, means at one end of the cartridge for supporting a lipstick therein, said cartridge in its entirety being freely slideable and rotatable in the bore of said body, said body having an aperture exposing the threaded portion of the cartridge sufficiently for engagement by a digit of the hand for manually rotating the cartridge in said body, means limiting movement of said cartridge in both directions in the bore of said body, thread engaging means formed from the material of said body to feed the cartridge longitudinally of the body in the manual rotation of said cartridge, said last named means comprising inwardly extending nubs formed from the material of said body and spaced longitudinally thereof, and said nubs being elongated and of a pitch corresponding to the pitch of the thread of said cartridge.
2. A lipstick holder comprising an outer tubular body having a longitudinal bore, a discharge opening at one end of said bore, a lipstick cartridge having a threaded portion on the periphery thereof extending substantially throughout the full length of the cartridge, means at one end of the cartridge for supporting a lipstick therein, said cartridge in its entirety being freely slideable and rotatable in the bore of said body, said body having an aperture exposing the threaded portion of the cartridge sufficiently for engagement by a digit of the hand for manually rotating the cartridge in said body, means limiting movement of said cartridge in both directions in the bore of said body, thread engaging means formed from the material of said body to feed the cartridge longitudinally of the body in the manual rotation of said cartridge, said last named means comprising inwardly extending nubs formed from the material of said body and spaced longitudinally thereof, and said nubs being circumferentially elongated.
3. A lipstick holder comprising a tubular casing, a lipstick supporting member mounted in said casing, said member having a spiral groove

75

forming a correspondingly spiralled gripper surface extending longitudinally of the member, the casing having intermediate its ends an aperture of such dimensions as to expose the gripper surface of said member therethrough for engagement by a digit of the hand in imparting rotary movement to said member within the casing, means extending into and spirally arranged on the casing adapted to operate in the spiral groove of said member in controlling the feed of said member longitudinally of the casing in both directions, and said last named means being circumferentially elongated on the casing.

4. A lipstick holder comprising a tubular casing, a lipstick supporting member mounted in said casing, said member having a spiral groove forming a correspondingly spiralled gripper surface extending longitudinally of the member, the casing having intermediate its ends an aperture of such dimensions as to expose the gripper surface of said member therethrough for engagement by a digit of the hand in imparting rotary movement to said member within the casing, means extending into and spirally arranged on the casing adapted to operate in the spiral groove of said member in controlling the feed of said member longitudinally of the casing in both directions, and said last named means being circumferentially elongated on the casing and inclined from right to left.

5. A lipstick holder comprising a tubular casing, a lipstick supporting member mounted in said casing, said member having a spiral groove forming a correspondingly spiralled gripper surface extending longitudinally of the member, the casing having intermediate its ends an aperture of such dimensions as to expose the gripper surface of said member therethrough for engagement by a digit of the hand in imparting rotary movement to said member within the casing, and the casing having inwardly extending means ar-

ranged above, below and at one side of the aperture therein, adapted to engage the thread of said member in controlling feed of the member longitudinally of the casing in the rotation of said member in both directions.

6. A lipstick holder comprising a tubular casing, a lipstick supporting member mounted in said casing, said member having a spiral groove forming a correspondingly spiralled gripper surface extending longitudinally of the member, the casing having intermediate its ends an aperture of such dimensions as to expose the gripper surface of said member therethrough for engagement by a digit of the hand in imparting rotary movement to said member within the casing, the casing having longitudinally spaced elongated nubbins inclined and spaced to fit the spiral groove of said member, and upper wall portions of the nubbins being relatively sharp to produce substantially wide bearing surfaces for engagement with upper edges defining said spiral groove.

7. A lipstick holder comprising an outer tubular body having a longitudinal bore, a discharge opening at one end of said bore, a lipstick cartridge having a threaded portion on the periphery thereof extending substantially throughout the full length of the cartridge, means at one end of the cartridge for supporting a lipstick therein, said cartridge in its entirety being freely slideable and rotatable in the bore of said body, said body having an aperture exposing the threaded portion of the cartridge sufficiently for engagement by a digit of the hand for manually rotating the cartridge in said body, means limiting movement of said cartridge in both directions in the bore of said body, and said body having a circumferentially elongated indenture engaging the thread of said cartridge to feed the cartridge longitudinally of the body in the manual rotation of said cartridge.

ALEXANDER S. MACKEY.
